US0D1107775S

(12) **United States Design Patent** (10) Patent No.: **US D1,107,775 S**
(45) Date of Patent: ** Dec. 30, 2025

(54) **CAMERA**(71) Applicant: **GoPro, Inc.**, San Mateo, CA (US)(72) Inventors: **Bessy Wen-Han Liang**, San Jose, CA (US); **Nicholas D. Woodman**, Big Sky, MT (US); **Nicholas Vitale**, Foster City, CA (US); **Huy Phuong Nguyen**, Alpine, UT (US)(73) Assignee: **GoPro, Inc.**, San Mateo, CA (US)(***) Term: **15 Years**(21) Appl. No.: **29/848,695**(22) Filed: **Aug. 4, 2022**(51) LOC (15) Cl. **16-06**

(52) U.S. Cl.

USPC ..... **D16/218**(58) **Field of Classification Search**

USPC D16/200-203, 206-209, 217-218, 220; D21/329, 514

CPC G03B 17/00; G03B 17/02

See application file for complete search history.

(57) CLAIM

The ornamental design for a camera as shown and described.

DESCRIPTION

FIG. 1 is a front, upper, left perspective view of a camera showing our new design in a first state of use;

FIG. 2 is a rear, lower, right perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a front, upper, left perspective view thereof in a second state of use;

FIG. 10 is a rear, lower, right perspective view thereof;

FIG. 11 is a front elevation view thereof;

FIG. 12 is a rear elevation view thereof;

FIG. 13 is a right elevation view thereof;

FIG. 14 is a left elevation view thereof;

FIG. 15 is a top plan view thereof;

FIG. 16 is a bottom plan view thereof.

FIG. 17 is a front, upper, left perspective view of another embodiment of a camera of our new design;
FIG. 18 is a rear, lower, right perspective view thereof;
FIG. 19 is a front elevation view thereof;
FIG. 20 is a rear elevation view thereof;
FIG. 21 is a right elevation view thereof;
FIG. 22 is a left elevation view thereof;
FIG. 23 is a top plan view thereof;
FIG. 24 is a bottom plan view thereof;
FIG. 25 is a front, upper, left perspective view of another embodiment of a camera of our new design;
FIG. 26 is a rear, lower, right perspective view thereof;
FIG. 27 is a front elevation view thereof;
FIG. 28 is a rear elevation view thereof;
FIG. 29 is a right elevation view thereof;
FIG. 30 is a left elevation view thereof;
FIG. 31 is a top plan view thereof;
FIG. 32 is a bottom plan view thereof;
FIG. 33 is a front, upper, left perspective view of another embodiment of a camera of our new design;
FIG. 34 is a rear, lower, right perspective view thereof;
FIG. 35 is a front elevation view thereof;
FIG. 36 is a rear elevation view thereof;
FIG. 37 is a right elevation view thereof;
FIG. 38 is a left elevation view thereof;
FIG. 39 is a top plan view thereof;
FIG. 40 is a bottom plan view thereof;
FIG. 41 is a front, upper, left perspective view of an embodiment of a camera of our new design in a first state;
FIG. 42 is a rear, lower, right perspective view thereof;
FIG. 43 is a front elevation view thereof;
FIG. 44 is a rear elevation view thereof;
FIG. 45 is a right elevation view thereof;
FIG. 46 is a left elevation view thereof;
FIG. 47 is a top plan view thereof;
FIG. 48 is a bottom plan view thereof;

FIG. 49 is a front, upper, left perspective view thereof in a second state;
FIG. 50 is a rear, lower, right perspective view thereof;
FIG. 51 is a front elevation view thereof;
FIG. 52 is a rear elevation view thereof;
FIG. 53 is a right elevation view thereof;
FIG. 54 is a left elevation view thereof;
FIG. 55 is a top plan view thereof;
FIG. 56 is a bottom plan view thereof;
FIG. 57 is a front, upper, left perspective view of another embodiment of a camera of our new design;
FIG. 58 is a rear, lower, right perspective view thereof;
FIG. 59 is a front elevation view thereof;
FIG. 60 is a rear elevation view thereof;
FIG. 61 is a right elevation view thereof;
FIG. 62 is a left elevation view thereof;
FIG. 63 is a top plan view thereof;
FIG. 64 is a bottom plan view thereof;
FIG. 65 is a front, upper, left perspective view of another embodiment of a camera of our new design;
FIG. 66 is a rear, lower, right perspective view thereof;
FIG. 67 is a front elevation view thereof;
FIG. 68 is a rear elevation view thereof;
FIG. 69 is a right elevation view thereof;
FIG. 70 is a left elevation view thereof;
FIG. 71 is a top plan view thereof;
FIG. 72 is a bottom plan view thereof;
FIG. 73 is a front, upper, left perspective view of another embodiment of a camera of our new design;
FIG. 74 is a rear, lower, right perspective view thereof;
FIG. 75 is a front elevation view thereof;
FIG. 76 is a rear elevation view thereof;
FIG. 77 is a right elevation view thereof;
FIG. 78 is a left elevation view thereof;
FIG. 79 is a top plan view thereof; and,
FIG. 80 is a bottom plan view thereof.
